UNITED STATES PATENT OFFICE.

ARNOLD KRIWAN, OF MARIEDORF, NEAR BERLIN, GERMANY.

ROLLING-MILL WITH SUPPORTED WORKING ROLLS.

1,360,959.

Specification of Letters Patent. Patented Nov. 30, 1920.

Application filed December 28, 1916. Serial No. 139,404.

To all whom it may concern:

Be it known that I, ARNOLD KRIWAN, engineer, a subject of the Emperor of Austria, residing at 74 Schwerinstrasse, Mariendorf, near Berlin, in the German Empire, have invented certain new and useful Improvements in Rolling-Mills with Supported Working Rolls; and I do hereby declare the following to be a full, clear, and exact description 10 of the invention.

My invention relates more particularly to that class of rolling mills for the elongation of material in which the working rolls are supported.

15 In rolling mills which are chiefly used for the drawing out of the material to be rolled, the diameter of the rolls should be as small as possible, because experience has shown that rolls of small diameter produce great 20 elongation of the material to be rolled.

These rolls of small diameter, however, show, under the counter-pressure of the material to be rolled, a considerable sagging or deflection and must therefore be supported.

25 For this purpose it has previously been proposed to adopt supporting rolls extending over the entire length of the working rolls and running in bearings in the housings; or supporting rails resting on the working rolls 30 and undergoing a shifting motion while the rolls are revolving. The known supporting rolls are applicable only for plain working rolls, and not for rolls having various diameters on their longitudinal extent. In 35 addition to this, there occur very strong pressures and frictional strains in the necks of the supporting rolls, so that special cooling arrangements have to be provided.

When making use of supporting rails, the 40 working length is limited by the length of the rails and, moreover, elaborate arrangements for supporting and guiding the rails become necessary.

My invention has for its object to eliminate the defects of these known arrangements and to provide for an effective cooling of the working rolls. According to my invention rings are used as supports for the working rolls of small diameter, such rings 50 revolving around fixed axles held by the housing frame, preferably by the insertion of balls or rollers between the rings and the axles.

In the accompanying drawings I show various forms of a rolling mill constructed in accordance with my invention.

Figure 1 is a vertical longitudinal section of a two-high rolling mill with five different sizes of passes, and Fig. 2 is a front view of the same mill in which one of the frames is 60 omitted.

Fig. 3 is a similar view of a rolling mill with supporting rings on both sides of the working roll.

Figs. 4 and 5 are views of a three-high rolling mill; Fig. 4^a is a diagrammatic view indicating the eccentric mounting of the rings b. Figs. 6 and 7 are views showing details and Fig. 8 shows a rolling mill with a cooling arrangement.

70 Referring to the drawings a working roll a of small diameter is supported at the working portions by rings b, which by the insertion of balls c or rollers, revolve freely on fixed axles d held by the frame e.

75 The supporting rings b are of a very large diameter in relation to the diameter of the working rolls a. The rolls and rings can revolve freely, whereby a great saving in power is effected.

80 Instead of arranging the supporting rings in an exactly vertical position above or below the working rolls, they may be arranged laterally in such a position as to receive the pressure on the working roll and in a manner similar to that already known in connection with supporting rolls. By such an arrangement the tendency of the working rolls 85 to creep up the face of the supporting rings is prevented.

90 If the rolling mill always works in one direction only, one supporting ring arranged laterally in such a position as to receive the pressure on the roll or one set of supporting rings for each working roll arranged in this 95 manner is sufficient. If, however, the rolling mill works alternately in different directions, supporting rings can be arranged on both sides of the working roll as shown in Figs. 3 and 4.

100 In a three-high rolling mill, it is possible to support the central working roll by the collars on the other working rolls. The central working roll is thus supported in a very efficient manner, even when the stress 105 is uneven. The stress becomes uneven on account of the fact that on the commencement of the rolling process, only the first pass is occupied, while the other passes are only gradually occupied one after the other.

110 The supporting rolls can be made non-circular in sectional form, so as to obtain vari-

ous thicknesses in one pass. In this manner, fashioned parts may be rolled.

As the position, which the supporting rings take with relation to the working rolls 5 must be exactly adjusted according to the work in hand and be altered if necessary, the normally fixed axles *d* of the supporting rings may be arranged in the housings in an adjustable manner.

10 Figs. 6 and 7 represent an example of such an adjusting arrangement.

The axle *d* is laterally adjustable in its bearing part *f* by means of screws *g*. The bearing part *f* which is guided at *h* may 15 further assume a different position in height by a lateral shifting of the wedge piece *z*.

The very considerable reduction in the diameter of the working rolls in consequence of the use of the supports described makes 20 it possible to cool them from the inside, and further, as the pressure on the bearings is very much reduced, to introduce a cooling liquid through the bearings of the rolls. Hitherto, this was not possible, as the cooling 25 liquids in question could not be introduced into the bearings in view of the high pressure on same and the high temperature.

Fig. 8 shows the cooling arrangement in which the cooling liquid is fed through pipe 30 *k* into an annular space *l* in the bearing *m* and then enters, through one or several holes in the neck, the hollow space *n* of the roll. From the bearing of one roll, *e. g.* the right 35 hand end of the lower roll in Fig. 8, the liquid passes to the interior of the roll through the hole *l*¹ and travels lengthwise of the roll through passage *n* to the opposite end thereof at which point it passes out through hole *l*² to the bearing at this end 40 and is led thence through piping *l*³ to the bearing of the roll above. Here it enters through hole *l*⁴ the interior passage *n*¹ of this roll and travels in opposite direction therethrough to the other end of this roll 45 where hole *l*⁵ communicates with the bearing above that of the lower roll at which the liquid enters through pipe *k*. The liquid may be led away from the upper roll through suitable piping,—possibly connected to a chamber communicating with the 50 passage *n*¹.

On the right hand side of Fig. 8 the roll end is shown bored from its outer end. The end opening of this bore will normally be 55 closed by a plug to prevent the escape of cooling fluid. By this arrangement, it is easy to obtain such a circulation of the cooling liquid through the rolls, necks and bearings as will meet requirements, and thus 60 obtain efficient cooling.

Two or more rolls may be cooled in the manner described.

It has previously been proposed, in the case of rolling mills, to cool the rolls, their

necks and bearings. The known arrangements for internal or external cooling, however, did not satisfactorily answer the requirements, as the feeding of the cooling liquid to the rolls and necks under great pressure did not assure a sufficient cooling. 70 These defects have been eliminated in the arrangement above described.

I claim:

1. In a rolling mill, a working roll and a supporting ring therefor, said ring rotating 75 on a fixed axis parallel to that of the working roll.

2. In a rolling mill, a working roll and a supporting ring therefor, said ring rotating on a fixed axis parallel to that of the working roll, together with anti-friction bearings between said ring and its fixed axis.

3. In a rolling mill, a plurality of stepped working rolls having a series of passes of different dimensions, and coöperating supporting collars on said rolls arranged between the passes.

4. In a rolling mill, a plurality of stepped working rolls having a series of passes of different dimensions, and coöperating supporting collars on said rolls arranged between the passes, together with supporting rings rotating on fixed axes parallel to those of the rolls and bearing against the top and bottom working rolls, for the purpose described.

5. In a rolling mill having more than two stepped working rolls with a series of passes of different dimensions, a working roll having a supporting collar arranged between 100 adjacent passes, and a coöperating collar on the adjacent intermediate roll.

6. In a rolling mill having more than two stepped working rolls with a series of passes of different dimensions, a working roll having a supporting collar arranged between 105 adjacent passes, and a coöperating collar on the adjacent intermediate roll, together with a supporting ring bearing against said working roll and rotating on a fixed axis parallel to that of the working roll.

7. In a rolling mill having more than two stepped working rolls with a series of passes of different dimensions, a working roll having a supporting collar arranged between 115 adjacent passes, and a coöperating collar on the adjacent intermediate roll, together with a supporting ring bearing against said working roll and rotating on a fixed axis parallel to that of the working roll, but out of vertical alinement therewith.

In testimony whereof I have signed my name to this specification, in the presence of two subscribing witnesses.

ARNOLD KRIWAN.
